GARMENT HANGER WITH MAGNETIC ACTION AND THE LIKE

Benjamin Weiss, Flushing, N. Y.

Application August 23, 1948, Serial No. 45,638

6 Claims. (Cl. 223—93)

1

This invention relates to garment hangers, particularly for fine dresses, and has for its main object to removably secure a garment on the hanger by magnetic action.

Another object of this invention is to provide a device as characterized hereinbefore, wherein the securing means may be easily and quickly applied, or removed in the same manner.

Another object of this invention is to provide in a device of this type, additional means, like spring elements, to additionally secure the garment on the hanger, and similarly an object of this invention is to provide additional means to protect the garment against dirt and dust, said protector preferably also being secured by the same magnetic action.

Still a further object of this invention is to provide novel securing spring action means and novel protector means for the garment, respectively, whether in combination with such magnetic securing means or without them.

Other objects of this invention will be apparent as the specification of the same proceeds, or will be pointed out therein, and, among others, I may mention: to provide devices as characterized hereinbefore, which with all the mentioned novel beneficial effects, still will be extremely simple in construction and inexpensive to manufacture.

In the drawings forming a part of this specification and accompanying the same:

Fig. 1 is a diagrammatical elevational view of a garment hanger to which the simplest form of my invention has been applied, and

Fig. 2 is a fragmentary sectional view thereof;

Figs. 3 and 4 are elevational and sectional views, respectively, of a modification;

Fig. 5 shows still a further modification;

Figs. 6 and 7 are front and top views, respectively, of a further modification;

Figs. 8 and 9 are fragmentary elevational and sectional views, respectively, of my invention for securing a garment on a hanger by magnetic action combined with shoulder protectors for the garment; and

Figs. 10 and 11 are front elevational and sectional views, respectively, of a modification of my combined garment securing and protecting means operating with magnetic action.

Referring now to the drawings, more in detail, by characters of reference, and particularly to Figs. 1 and 2, the numeral 20 indicates a garment hanger, in general, having the yoke 21 and the hook 22 and being of any usual construction. However, in this embodiment of my invention, the yoke 21 is contemplated as made of magnetiz-

2

able material, like iron, steel, nickel, or other appropriate metals or alloys, and, obviously, the yoke may have different forms than the plate like one illustrated.

I provide a small permanent magnet 23 which, again, may have any desired appropriate shape and size, and preferably may be of a strong magnetic alloy, many of them being well known in this art. The garment is indicated in a diagrammatic manner by dot and dash lines at 24, and after the same has been draped on the yoke of the garment hanger, as shown, a magnet piece 23 will be placed over the same at an appropriate portion thereof whereby the strong attraction between the magnet 23 and the magnetizable yoke 21 will press the magnet piece on the garment and therethrough on the yoke and thereby secure the garment on the hanger and prevent its slipping off.

In the embodiment shown there are two magnetic securing pieces 23 used for the two shoulder portions of the garment.

I may also provide a cord 25 for each magnet piece by which the same may be tied on an appropriate portion of the hook 22, as indicated at 26.

When it is desired to remove the garment, the magnet piece 23 will be lifted from the yoke 21 and the cord 25 is provided only to prevent a misplacing or loss of the magnet piece 23, and to have it readily available when a new garment is placed on the hanger. Of course, the cord 25 may be of decorative material, like a tassel in case of more decorative or expensive hangers.

In Figs. 3 and 4 I indicate a modification of my invention wherein the hanger, generally indicated by the numeral 21, is made of non-magnetizable material, preferably of plastic, and preferably formed of one piece with its hook 28. Magnet pieces, similar to the ones described hereinbefore are employed here also, and they may be secured at the ends of the cords 25.

A second piece of permanent magnetic alloy indicated by the numeral 29, however, is employed on each side of the yoke 30. In this embodiment the magnet piece 29 is incorporated into a sleeve 31 preferably made of rubber so that it may be slipped on any yoke, as indicated in the drawings. The garment will be draped over the hanger and over the sleeve 31 with the magnet piece 29 therein, and the securing magnet piece 23 will be placed thereover, whereby the attraction between the two magnet pieces 23 and 29 will secure the garment on the hanger. Of course, the magnet piece 29 may be placed in any other

position than on the top of the yokes, as shown, like on the side of the garment hanger, and then the coacting loose piece 23 will be placed in a corresponding position.

Fig. 5 shows a comparatively small change in the embodiment of Figs. 3 and 4 whereby the movable securing magnet piece 23 is arranged at the end of an arm 32, pivoted on the hanger, as at 32a, so that when the garment is to be removed, the arm 32 will be raised, as indicated by the arrow 32b, while when the garment is to be secured on the hanger, the arm 32 will be lowered until its magnet 23 will be over the magnet 29 in the securing sleeve 31 on the yoke. Obviously, magnet 29 may be secured on the yoke by any other appropriate means, like being embedded therein.

In Figs. 6 and 7 still a further modification of my invention is shown. In this embodiment the garment hanger, indicated in general by the numeral 33, will have the yoke 34, and will have two arms 35 thereabove, which may be of any appropriate construction. In the embodiment shown, the garment hanger with its arm 35 is formed of one piece of plastic material, the upper end of its hook being shown as broken away. Arms 35 will be made resilient so that they can be bent out of the plane of the garment hanger and permitted to snap back towards the same when released. They also will be curved downwardly so that their lower terminations 36 will be against a corresponding portion of the yoke 34. The permanent magnet 23 will be secured at said termination and facing the yoke, while the corresponding magnet 29 will be secured on the yoke in a registering position therewith when the same is closed on the yoke, as indicated in the drawings. Obviously, a garment draped on the yoke will be held by the two pressures exerted thereon through the attraction between the magnets and through the spring action of the arms 35, respectively.

When it is desired to remove the garment, the arms 35 will be bent rearwardly, as indicated by the arrow 37 and by the dotted position of the arms in Fig. 7, and when a new garment has been draped on the yoke, the arms 35 will be permitted to snap back and secure it through spring and magnetic actions. Of course, the arms 35 in this case may be operative even without the magnet simply by their own resilient pressures on the garment and on the yoke.

In Figs. 8 and 9 the application of my invention for a protector for the shoulders of the garment is shown which is also adapted to secure the garment on the hanger. In this embodiment, the garment hanger is indicated, in general, by the numeral 40 having the yoke 41 and the hook 42. A shoulder protector 43 is draped over each side of the yoke, each protector, in the embodiment shown, simply is a flexible piece of material, like fabric. The magnet 44 is secured on, or is embedded in the flexible protector 43. In Fig. 9 it is indicated in the branch or portion 45 of the protector. A magnet 46 is embedded in the yoke 41. When a garment is draped over the yoke, the protector 43 will be folded thereover, its magnet 44 being placed registeringly with the magnet 46 in the yoke and thereby not only will the garment be secured on the yoke by a magnetic action, but the protector 43 will also be held by the attraction between the two magnets.

In Figs. 10 and 11 a modified form of the invention of Figs. 8 and 9 is shown. In this embodiment the garment hanger is indicated, in general, by the numeral 50, having a yoke 51 and a

hook 52. An arm 53 is provided on the garment hanger above each side of the yoke, spaced apart therefrom. The protector, generally indicated by the numeral 54, will again be in the form of a flexible loop having the two branches or sides 55 and 56 interconnected as at 57. However, the protector is secured at its top 51 to a sleeve 58 which may be pulled on the respective upper arm 53 of the hanger. A magnet 59 is secured within the branch 56 of the protector, and opposite thereto, a magnet 60 is secured in the yoke 51.

It will be seen that the magnets 59 and 60 will secure the garment, indicated in an imaginary manner by dot and dash lines at 61, on the yoke 51, and at the same time they additionally secure the protector 54. When it is desired to remove the garment, the front flap 55 of the protector may be thrown upwardly and over the arm 53, as indicated by its dotted line position in Fig. 11, and when a new garment is placed on the hanger, the flap 55 may be dropped into its full line position to protect the shoulder of the garment. This protector obviously may be used even without any magnetic securing of its flaps on the yoke, or vice versa, a second pair of magnets 59 and 60 may be employed on the flap 55.

Obviously the principle of my invention may be used in other forms of garment suspending devices than the hangers shown hereinbefore, and for other cases than garment devices. So I am contemplating the use of my invention for trousers and skirts suspending devices, wherein the object may be placed between two receiving elements in the suspending device and the elements enclosed thereon by magnetic action.

While several modifications of my invention have been shown and described in this specification, I want it to be understood that further variations and changes may be made in the elements, constructions, combinations and operations of my invention, and I reserve my rights to all the changes and variations as are within the spirit of the present specification and the scope of the claims hereunto appended.

Having thus described my invention, what I claim as new and desire to protect by Letters Patent of the United States, is:

1. In a garment hanger, an element to receive a garment draped thereon, said element comprising a suspension member and arms extending outwardly from the opposite sides thereof, a magnetic member adapted to be removably placed over the garment, magnetic means on the garment receiving element adapted to react to said magnetic member and thereby temporarily secure the same and therethrough the garment on said receiving element, said magnetic member being carried by a portion of said hanger relatively movable with reference to said garment receiving element.

2. In a garment hanger, an element to receive a garment draped thereon, said element comprising a suspension member, and arms extending outwardly from the opposite sides thereof, a magnet adapted to be removably placed over the garment when on said hanger, means to movably connect said magnet to said element and magnetic means in the hanger adapted to react to and provide an attaching force for said magnet and thereby temporarily secure the same, and therethrough the garment, on the hanger.

3. In a device, as set forth in claim 2, said magnetic means to magnetically attach said magnet to said element being in the form of a portion of

said element over which said magnet is placed and being made of magnetizable material.

4. In a device, as set forth in claim 2, said magnetic means to magnetically attach said magnet to said element being in the form of a second magnet secured on said element, said first magnet being placed thereagainst.

5. In a garment hanger, an element to receive a garment draped thereon, said element comprising a suspension member, and arms extending outwardly from the opposite sides thereof, a magnetic member adapted to be removably placed over the garment draped on said element, magnetic means on the garment receiving element adapted to react to said magnetic member and thereby temporarily secure the same and there-through the garment on said receiving element, and means to movably connect said magnetic member to said garment receiving element, and said magnetic means being carried on a sleeve 20 slidable on said element.

6. In a garment hanger, an element to receive a garment draped thereon, said element comprising a suspension member, and arms extending

outwardly from the opposite sides thereof, a pair of magnetic members adapted to be removably placed on the arms of said element and over the garment draped thereon, a pair of resilient sleeves 10 slidably mounted on said arms, respectively, and magnetic means on said sleeves adapted to react with said magnetic members, respectively, to thereby temporarily secure the same and there-through the garment on said receiving element, and means to movably connect said magnetic members to said element.

BENJAMIN WEISS.
